UNITED STATES PATENT OFFICE.

ERNST A. H. JACOB, OF SAN ANTONIO, TEXAS.

COTTON PACKER.

Application filed March 25, 1922. Serial No. 546,836.

To all whom it may concern:

Be it known that I, ERNST A. H. JACOB, a citizen of the Republic of Germany, residing at San Antonio, in the county of Bexar and State of Texas, United States of America, have invented a new and useful Cotton Packer, of which the following is a specification.

My invention relates to improvements in cotton packers of that general type in which a vertically reciprocating plunger operates in a press-box, means being provided for feeding the cotton into the press-box below the plunger.

15 The objects of my invention are:

First, to provide a cotton packer of the general type used in cotton gins, and of such a structure that any individual machine can be easily and quickly adapted to location in 20 a cotton gin as either a right-hand or a left-hand machine;

Second, to provide such a unity of structure in the packer that the single element of motive power that drives the reciprocating plunger in the press-box shall drive also the feeder;

Third, to provide new and improved driving means for the plunger;

Fourth, to provide driving means for the plunger which, when the motive power is disconnected, will itself positively hold the plunger stationary in any position desired, and thus eliminate the need for a special brake or holding device;

35 Fifth, to provide such unitary means to render the operating means inoperative, as will, subject to the will of the operator, cause the plunger, either (1) to remain stationary at any desired position in relation to the press-box, or (2) to stop automatically at the topmost point of its upstroke irrespective of the time of actuation of said means;

40 Sixth, to provide novel mechanism for the automatic intermittent operation of the feeder;

45 Seventh, to provide a feeder of extremely simple and efficient design;

50 Eighth, to provide a cotton packer simple, firm, and compact in structure, lasting in quality, and easily and economically built.

I attain these objects by the mechanism illustrated in the accompanying drawings, in which,—

Figure 1 is a side elevation of the complete machine; Figure 2 is a sectional view of the worm, the worm gear, and the radius arm; Figure 3 is a plan view of the cotton packer; Figure 4 is a plan view of the shaft carrying the belt-shifter arms together with 55 the parts directly coacting therewith when these members stand in normal relationship; Figure 5 is a vertical sectional view taken on the line 5—5 of Figure 1 looking toward the rear; Figure 6 is a section taken on line 60 6—6 of Figure 3 looking toward the rear; Figure 7 is a front elevation of worm and worm gear partly in section taken on line 65 7—7 of Figure 1.

Similar numerals refer to similar parts 70 throughout the several views. The frame 1 is rigidly fastened on sills 2. Frame 1 is supplied with guides 3 on which the plunger 4 is mounted for vertical reciprocation. The plunger 4 including the platen 5 carries a 75 gate 6 coacting with hopper 43 and operating within the press-box 21.

The plunger 4 includes a double-sided free-ended rack 7, including a bar 8 and a bar 8¹. Bar 8 is fastened at its upper extremity to the cross-plate 10 which with cross-plate 10¹ rigidly holds in relative vertical position the uprights 12 and 13. At its lower end bar 8 is rigidly secured to cross-plate 14 similar to cross-plate 10, and, 80 on its front side, to cross-plate 14¹ similar to 10¹. The uprights 12 and 13 are rigidly fastened in relative position at their lower ends on platen 5. Bar 8¹ is free-ended being supported in front of, and parallel with, 85 the bar 8 by a plurality of pins 9 regularly spaced apart in vertical alignment. The rack 7 cooperating with pinion 15 carried by shaft 16 journalled in the lower end of a radius arm 17 mounted to oscillate on a 90 shaft 18 mounted on the horizontal part 19 of frame 1. On that end of shaft 16 opposite to pinion 15, is fixed the worm gear 20 which meshes with worm 21 fixed on driving shaft 22 which is journalled in extensions 95 23 of frame 1. Guard 24 covers worm 21 and associated elements. The extensions 23

are each in two parts; the lower part of each extension is integral with frame 1; the upper part of each extension is a separate plate. Both extremities of the drive shaft 22 extend well beyond the extensions 23 of frame 1, and are each adapted to receive a fixed pulley 25 and a loose pulley 26 with which is adapted to coact driving belt 27 leading from a suitable source of power. 10 The location of the source of power determines the location of pulleys 26 and 27, whether on the right hand or left hand extremity of shaft 22.

When the source of power is operatively connected by means of belt 27 and fixed pulley 25 with drive shaft 22, drive worm 21 rotates worm gear 20 and shaft 16. Shaft 16 rotates pinion 15 which coacts with rack 7 causing the reciprocation of plunger 4. As shaft 16 begins rotation, radius arm 17 swings out on either side of the rack 7, this movement being sufficiently to one side of the perpendicular to allow of the vertical movement of plunger 4 including rack 7. 20 As the exertion of the power continues, pinion 15 forces plunger 4 upward and downward in regular practical reciprocation. As the radius arm 17 swings out on either side of the rack 7 to allow said rack passage room, 30 said radius arm comes in contact with stop 17¹ which holds pinion 15 in operative position with respect to rack 7 until the end of rack is reached when loose roller 15¹ comes in contact with the concave edge of plate 10¹ or of plate 14¹ and the radius arm 17 swings sufficiently to allow pinion 15 to pass to the opposite side of rack 7 where its operative influence continues. The swinging of the radius arm 17 induced by the operative relation of the pinion 15 with the rack 7 and controlled by the stops 17¹ and the curved edges of plates 10¹ and 14¹ moves the worm gear 20 from side to side in a radial relationship to the drive worm 21 40 with no interruption of the driving connection which is always positive. The swinging of the radius arm has the advantage of providing this positive drive and permitting at the same time vertical reciprocation of the plunger. The operation of the driving means, including particularly the operation of the drive worm and of the plunger, is quiet and powerful.

55 The means of shifting the belt 27 relative to the pulleys 25 and 26 as herein embodied, comprises the following described combination of elements. Shaft 28 carrying conventional belt-shifting arms 29 slides in bearing 30 and in hollow shaft 31. Arms 60 32 are pivotally clamped to shaft 28 and to arm 33. Arms 34 are pivotally fastened to the outer extremity of hollow shaft 31 and to arm 33. Arm 33 is joined universally at its outer end to lever 35 which is fulcrumed in a universal joint on support 36 mounted

on guard 24. To the outer end of hollow shaft 31 is pivotally fastened lever arm 37 fulcrumed on pin 38 which is mounted in boss 39 on frame 1. Lever arm 37 is pivotally connected with a shifter bar 40 adapted to coact with shifter plate 41 mounted near the lower end of bar 8 of plunger 4. Shifter bar 40 slides in bearings provided in frame 1. Shifter bar 40 is reversible in position relative to frame 1; and plate 41 has a bevel edge extending on each side of bar 8 in order to be adaptable to coact with shifter bar 40 in either of its alternative positions. The entire shifting mechanism is reversible in position relative to frame 1 in order to be adaptable to either right or left hand drive. Bearing 30 is positioned on frame 1 and is adapted for location on either side of said frame 1. A boss 39 furnishing means to mount pin 38 which provides the fulcrum point for the lever arm 37 is provided on either side of frame 1. The shaft 28 carrying the arms 29 can be simply reversed in its position across the top of the frame. Thus the entire shifting device is reversible and adaptable to coact with a drive belt running on pulleys mounted on either end of the drive shaft 22 mounted on frame 1. This characteristic of the packer is valuable inasmuch as all machines embodying my present invention are made generally alike, and no provision in time or expense need be made by manufacturer or buyer for building, choosing, or supplying a machine built especially for right or left hand use.

100 The belt-shifting device described above is compound in its automatic operation. A sufficient force exerted by the operator outwardly at the lower end of the lever bar 35 when arm 33 is practically in line with arms 32 and when shifter arms 29 are in position on that side of the frame next to arms 32, moves the belt 27 from the fixed to the loose pulley, and the plunger stops immediately and remains motionless in the position where 110 stopped. Said force moves the arms 32 and 34 in an angular position opposite their normal relative position, and the spring 34¹ holds them in such position insuring a positive retention of belt 27 on loose pulley 26. 115 A stop-bolt 33¹ extending through the spread arms on the end of arm 33 prevents the spring 34¹ from drawing the shaft 28 back into the hollow shaft 31. The result is a solid bar effect holding the belt 27 firmly on the loose pulley 26 until such time as the said force is exerted on the lower end of the lever 35 in the opposite direction to its previous exertion that is toward the packer frame, in which case the arms 32 and 34 resume their normal angular relative position and the shaft 28 is drawn into the hollow shaft 31 drawing with it the arms 29 which shift the belt from the loose pulley 26 to the fixed pulley 25, and the source of power being 130

connected with the driving means, the plunger resumes its travel. One advantage of this mode of operation is that in case of fire in the press-box, the platen can be run down 5 sharply against the cotton and stopped and held there.

As an alternative, and more usual, manner of operating the belt-shifting device, the 10 said force is exerted outwardly, by the operator, at the lower end of lever bar 35 when arm 33 is practically in line with arms 34 and when shifter arms 29 are in position on that side of the frame next to arms 32. Said force thus exerted operates through lever 15 arm 37 to force shifter bar 40 across frame 1 in such manner that the edge 42 coacts with the bevel edge of shifter plate 41 as the plunger 4 comes to its highest point of travel. The shifter bar 40 is then forced 20 back across the frame 1 in an opposite direction from its first movement and operates lever arm 37 to move drive belt 27 from fixed pulley 25 to loose pulley 26, the arms 32 and 34 and the spring 34¹ coacting as in the alternative 25 manner of operating the shifting device. One advantage of this mode of operation is that the person attending the packer may give the impetus for stopping the plunger at any time during the travel of 30 said plunger, and the plunger will stop only when it reaches its highest point of travel. This characteristic of my invention is of great value for the reason that a great saving of time at critical moments is effected 35 and also for the reason that a precise and positive stopping point for the plunger is assured without any cost in time and attention on the part of the attendant.

The manner of operation of the belt-shifting 40 device is not affected by a reversal of position relative to the frame of the parts of the device to accommodate the machine for right or left hand drive. I have described a preferred form of this part of my invention; 45 other forms embodying the same principles may be employed in putting the invention into practice.

The cotton is intermittently fed from the 50 hopper 43 by automatic means into the press-box 2¹. A loose shaft 44 is positioned lengthwise in the hopper 43. Fixed on the shaft 44 is a fan or feeder 44¹ made of two boards positioned in a plane on opposite sides of shaft 44 and having beveled edges in order 55 that the feeder in operation may at each revolution the more smoothly disengage from the cotton. Shaft 44 extends some distance in both directions through the ends of hopper 43 and is supported at one end in a 60 suitable bearing by a hanger 45 mounted on the sill 2. The opposite end of shaft 44 has considerable play in an aperture through the other end of hopper 43, and has fixed upon it a pulley 46 and lever 47 fulcrumed 65 at one end on supporting member 48 and

actuated to function by the rod 49. During the upward movement of the plunger the cam member 50 carried thereby coacts with the roller 51, carried by the lever 52, the transmitting shaft 53, the lever 54, rod 49, 70 and lever 47 to raise the pulley 46 into contact with continuously moving friction pulley 55 whereupon rotation is imparted to feeder 44¹ for the movement of cotton into the press-box. As soon as the plunger has moved far enough on its downward travel to withdraw the cam member 50 from contact with the roller 51, the weight of the pulley 46 and of the fan 44¹ withdraws the pulley 46 from contact with the friction pulley 55 and brings said pulley 46 into contact with brake shoe 56, which contact instantly stops the rotation of feeder fan 44¹. It will be noted that the rotation and the inaction of the feeder 44¹ are both positive, and that the feeder will discharge cotton into the press-box only when the plunger and accompanying gate are high enough in the course of their upward travel to allow the cotton to pass freely into the press-box. The 80 gate 6 prevents loose cotton working into the press-box on top of the plunger during the inaction of feeder 44¹.

Friction pulley 55 is in continuous operation when the source of power is operatively 95 connected with shaft 22, friction pulley 55 being fixed on shaft 57 which bears also fixed pulley 58 actuated by belt 59. Belt 59 runs upon loose pulleys 60 and 61 and is actuated by pulley 62 fixed upon shaft 22 100 on which drive worm 21 is fixed. Thus the one shaft 22 receives power through belt 27 and fixed pulley 25 delivering the power to both the plunger and the feeder. The actuation, and control of the one power shaft 105 provides a simple, unified, and positive control of both plunger and feeder by the same impulse, which combination does away with considerable looseness in the operation of the packer. It will be noted that the shafts 110 supporting the pulleys 55, 58, 60, 61 are mounted in a strong casting 48 fixed by bolts 63 on sill 2. The combination of elements comprising the feeder and its connections with the power, is compact and efficient. The machine is made principally of iron and steel, and is of particularly solid and unified structure. Its operation is marked by highly dependable qualities; and its automatic features result in improved 120 work accomplished in a convenient manner. The machine itself is easily and simply made, and is economical in manufacture.

I claim:

1. In a cotton packer, the combination of 125 a reciprocating plunger, a shifter plate carried by said plunger, an intermittent feeder, said feeder being adapted to function under the influence of the movement of said plunger, common means for operating said plun-

ger, said feeder, and belt shifting means for rendering said belt shifting means inoperative, said means being adapted to take effect instantly upon actuation regardless of the location of the plunger or to take effect automatically through the shifter plate when plunger is at the highest point of its upward stroke.

2. In a cotton packer, a frame, a reciprocating plunger, driving means for said plunger comprising a drive shaft mounted on said frame, a radius arm, a rack, a shaft mounted in said arm and adapted to oscillate in an arc on one end of the frame, a pinion fixed on said last named shaft and adapted to coact with said rack, a worm gear fixed on the other end of said shaft and adapted to coact with a worm fixed on the drive shaft, said drive shaft being mounted on said frame and adapted to receive power through a pulley mounted on either of its extremities.

3. A cotton packer comprising a frame, a press-box, a plunger mounted to reciprocate in the frame and cooperating with the press-box, the plunger comprising a double-sided, free-ended rack, a radius arm mounted at its upper end to oscillate in an arc on the frame, a pinion carried by the lower end of the radius arm and cooperating with the rack, and means for rotating the pinion by a worm gear, and means for keeping said pinion in continuous operative relation with said rack.

4. A cotton packer, a frame, a press-box, a reciprocating plunger, means for operating said plunger, said means including an oscillatory radius arm and a pinion carried thereby, means for rendering the operative means inoperative, including a belt shifting assembly said operative means when in inoperative position co-operating with the frame to form a lock which holds the plunger in any desired position relative to the press-box.

5. A cotton packer comprising a frame, a press-box, a reciprocating plunger, means for operating said plunger, and means for rendering said operative means inoperative, said last-named means comprising a belt shifting assembly, said means being adapted to take effect instantly upon manual actuation of the belt shifting assembly regardless of position of plunger or to take effect only when the plunger is at its highest point of travel relative to the press-box.

6. A cotton packer comprising a reciprocating plunger, means for operating said plunger, means comprising a belt shifting assembly for rendering said means inoperative, at any position of said plunger relative to the press-box manually, or of rendering said operating means inoperative automatically by a stop on plunger at end of upstroke of said plunger, said plunger

being automatically locked in position by worm gearing.

7. A cotton packer comprising a frame, a press-box reciprocating plunger co-operating with the press-box, a hopper discharging in advance of the plunger, a rotary feeder mounted in said hopper, a single fixed pulley carried by the feeder mechanism, said pulley receiving its power by coacting with a friction pulley, a belt from main drive shaft coacting with said friction pulley shaft, and means for intermittently maintaining the feeder pulley in engagement with said rotary friction pulley.

8. A cotton packer comprising a frame, a reciprocating plunger in said frame, a hopper discharging in advance of the plunger, a rotary feeder within the hopper, the rotary feeder being rendered inoperative by a cam moving out of contact with roller allowing levers to drop the feeder pulley from contact with the friction pulley.

9. A cotton packer comprising a frame, a plunger, a hopper discharging in advance of the plunger, a feeding member within the hopper, a loose shaft carrying the feeding member, a fixed pulley mounted on said shaft, for intermittent contact with a friction pulley operatively connected with a source of power, said contact being induced by levers actuated by a cam mounted on said plunger.

10. A cotton packer comprising a frame, a reciprocating plunger cooperating with said frame, an intermittent feeder cooperating with said plunger, a source of power, operative means including worm gearing connecting said plunger with said source of power, and operative means including an intermittently operating friction pulley connecting said feeder with said source of power.

11. A cotton packer comprising a frame, a reciprocating plunger, a hopper discharging in advance of the plunger, and a feeder comprising two blades disposed in fixed relation one on each side of a rotary shaft in a common plane to rotate therewith.

12. In a cotton packer, in combination, a feed hopper, a loose, vertically movable, rotary shaft mounted lengthwise in said hopper, said shaft carrying propellers fixed thereto in a plane said propellers adapted to rotate with said shaft.

13. A cotton packer, comprising a frame, a reciprocating plunger in said frame, a hopper discharging in advance of the plunger, a rotary feeder within the hopper, the rotary feeder being rendered inoperative by a cam moving out of contact with the roller allowing levers to drop the feeder pulley from contact with the friction pulley, into a brake and stop the movement of feeder immediately.

14. A cotton packer comprising a frame, a reciprocating plunger in said frame, a cam mounted on said plunger, a hopper discharging in advance of said plunger, a rotary feeder within the hopper, a fixed pulley carried on the shaft of said feeder, said rotary feeder being rendered inoperative by a cam moving out of contact with the roller allowing levers to drop said feeder pulley from contact with the friction pulley, and 10 a brake block onto which said fixed feeder pulley drops, whereby to immediately stop said feeder.
